GONDOLA CAR TOP CHORD ANGLE AND
LADING TIE ANCHOREdward Payson Smith, Winnetka, Ill., assignor
to Illinois Railway Equipment Company, Chi-
cago, Ill., a corporation of Illinois

Application March 19, 1951, Serial No. 216,315

6 Claims. (Cl. 105—369)

1

My invention relates to top chords, with incorporated lading tie anchors, for gondola cars, whereby a steel chord of great strength is provided with non-protruding anchors, which permit the tie means to be disposed at varying degrees to the vertical axis of the anchors, thus permitting the tie straps or elements to extend in directions toward opposite ends of the car and respond to the pulling strains without undue or tearing strains.

My invention lends itself to the making of the combined unit of suitable metal, preferably cast steel, made in preselected sections for convenience in handling which may then be integrally united by welding, without, however, materially increasing initial cost.

The aforementioned objects and advantages of my invention will be readily comprehended from the following detailed description of the accompanying drawing wherein:

Figure 1 is a top plan view of a section of my improved top chord.

Figure 2 is a side elevation thereof.

Figure 3 is a cross sectional view taken on the line 3—3 of Figure 1.

Figure 4 is a similar view on the line 4—4 of Figure 1.

Figures 5 and 6 are similar views taken respectively, on the lines 5—5 and 6—6 of Figure 1.

Figure 7 is a perspective view of a section of the car top angle involving my invention.

My invention relates to an improved top chord for gondola cars, with lading tie anchors incorporated therein, and which is adapted to be welded or otherwise intimately secured to the top edges of gondola car walls; the improved chord, for the sake of easier manipulation in installation, being preferably cast or formed in sections of preselected length adapted to be arranged in abutting relation on the car wall and to the respective sections welded together and to the car wall and formed to provide greater strength than that of present-day constructions.

My invention is designed to enable use of the conventional steel strapping as well as steel wire and thus enable a proper and secure anchoring of the commodity to be provided without damage to the car sides. Due to the failure in providing proper anchoring means, shippers have been known to burn holes in the sides of the car, thereby weakening the car construction, inducing deterioration and tie means cutting surfaces.

As my improved top chord angle, which extends about the entire car, for the sake of easier manipulation, preferably is formed in preselected

2

lengths of similar contour, the illustration and description of a single section of my improved top chord and tie strap anchor will suffice. The number of chord sections, of course, may depend on the length of the car and its design determines the side post or stake spacing, which in turn suggests the number of chord sections required to provide a top chord angle throughout the length of the car.

10 Each chord section 15, which I prefer to form of cast steel, and for purpose of strength is of substantially right-angular cross-section, with its inner leg or uninterrupted side 16 arranged in lapping relation with the inner face of car 15 side wall 17, as shown in Figure 7, to which it is integrally secured as by welding. The other leg or side 18 overlaps the top edge of the gondola car side wall and extends substantially horizontally outward from the car wall. This leg or 20 side 18 terminates in a downwardly disposed flange 19, which at preselected distances apart is provided or cast with the tie strap anchors shown at 20, 20 in Figure 7.

The strap anchors are formed by depressing 25 a part of the top side to provide the dependent wall portion, as shown at 21; and providing the outer edge or rim of the cavity with the depending or underslung loop 22, which extends slightly beneath the lower edge of the dependent 30 wall portion 21 and spaced therefrom to provide the anchor strap receiving opening at 23.

The underslung loop 22 preferably is provided 35 with rounded surfaces to enable easy movement or insertion of the lading tie strap; with one end of the loop, namely, the end at the left of the anchor at the left in Figure 7, provided with a long downward slope as shown at 24; while the opposite end of the loop is short and at a sharper degree as shown at 25.

40 I prefer to arrange these anchors in pairs as shown, with the loop at the right sloping exactly opposite to the one at the left, thus permitting the tie bands to angle seventy degrees to the right of vertical in the right hand anchor as indicated by the band section 26, or permit the tie bands to angle say fourteen degrees at the opposite ends of the anchors as shown at 27 in Figure 2.

45 It will be understood that similar anchors are provided in the top chord of the opposite side wall of the car and that each top chord section will present, at least preferably, a pair of lading strap anchors.

50 The length of the car and its design determine the side post or stake spacing which in turn sug-

gests the required number of chord sections necessary for a complete chord about the top of the car; the various sections being arranged in end to end abutting relation and welded together as indicated at 28 in Figure 7, to provide a rigid unitary structure about the top edge of the car.

I also provide each chord section 15, intermediate the band anchors 20, 20, with a suitable hole 29 to accommodate a steel rod used for holding certain types of lading.

My improved chord section thus provides for use of various types of lading tie means without in any way weakening the top chord or car construction while presenting a smooth surfaced top chord with anchor sections which will not interfere with loading and unloading operations.

In present-day gondola car construction, the top chord angle comprises a rolled steel section that ties the side plates and spaced vertical posts into a rigid unit which, in various types to obtain desired strength, are augmented by welding a flat steel strap of comparatively heavy cross-section. The angle member and the reinforcing strap at spaced intervals along the car length have holes adapted to the use of small rods or wire for holding the car lading. This method is undesirable and inefficient with certain lading and does not permit the use of the present-day conventional steel strap tie means. My improved combined top chord with incorporated tie-strap anchors obviates the necessity and expense of applying various types of lading band holding anchors; of adding auxiliary strength-providing members; and the time and labor involved in punching the rod-receiving holes heretofore mentioned, as the respective chord sections preferably have two band anchors and a rod-receiving opening incorporated therein and all recessed to prevent being engaged by an article rubbing across the bulb or top chord.

The structure shown and described is believed to be the preferred form of my invention which has been described in terms of description and not in terms of limitation, as structural modifications may be possible and may be made without, however, departing from the spirit of my invention as defined in the appended claims.

What I claim is:

1. A gondola car top chord of angle cross-section whose vertical side or leg is adapted to be welded to the upper marginal portion of the car wall with the horizontal side or leg disposed outwardly across the car wall and provided with a downwardly disposed flange, said horizontal leg at preselected intervals having lading tie strap-receiving elongated holes defined at one side by

vertical downwardly disposed wall portions and at the outer side by downwardly sloping loops.

2. A gondola car top chord of angle cross-section whose vertical side is adapted to be intimately secured to the upper marginal portion of the car wall, while the horizontal side of the angle extends outwardly across the car wall with the horizontal side at preselected intervals having lading tie strap-receiving openings provided at 10 the inner sides with downwardly extending flat walls and at their outer sides with downwardly extending tie strap-holding loops whose ends curve upwardly at different degrees of slope relative to the vertical axes through the loops.

15. 3. A gondola car top chord of angle cross-section whose vertical side is adapted to be intimately secured to the upper marginal portion of the car wall, while the horizontal side of the angle at preselected intervals is cast with lading strap-receiving openings provided at their inner sides with downwardly disposed strap-guiding portions and at their outer sides with underslung loop-like portions of arcuate cross-section to provide tie strap-holding portions.

25. 4. A gondola car top chord of right angular cross-section whose vertical side is adapted to be intimately secured to the upper marginal portion of the car wall, while the horizontal side of the angle at preselected intervals is provided with depressed lading strap-receiving openings having downwardly extending rear walls and depending loop-like portions disposed longitudinally at the outer sides of the openings and disposed beneath the plane of the upper surface of the horizontal 30 side and curving upwardly toward the ends of the openings.

35. 5. A gondola car top chord of right angular cross-section whose vertical side is adapted to be intimately secured to the upper marginal portion 40 of the car wall, while the horizontal side of the chord at preselected intervals is depressed to form loop-like portions disposed below the horizontal side and provide tie strap passages about the loop-like portions.

45. 6. A gondola car top chord composed of a plurality of right angular sections arranged end to end and welded into a single chord, with one side of each section intimately secured to the top edge of the car wall while the other side of each section 50 extends horizontally and is provided with elongated openings and the metal at the outer sides of the openings depressed below the horizontal side of the section into lading tie strap attaching loops.
